UNITED STATES PATENT OFFICE.

ALPHONSO T. PALMER, OF CHICAGO, ILLINOIS.

RAIL ANCHOR.

Application filed October 22, 1926. Serial No. 143,359.

This invention relates to a device for gripping a railway rail to hold the same from longitudinal movement over the supporting ties, and has for one of its objects the provision of such a rail anchor which shall be convenient to apply and which shall effectively grip the rail to prevent movement thereof.

Other objects will appear from the following description.

The invention is exemplified in the combination and arrangement of parts shown in the accompanying drawing and described in the following specification, and it is more particularly pointed out in the appended claims.

In the drawing—

Fig. 1 is a top plan view of a rail anchor showing its position relative to the rail and tie plate;

Fig. 2 is a section on line 2—2 of Fig. 1;

Fig. 3 is an elevation looking from the right in Fig. 1, showing the parts in process of application;

Fig. 4 is a perspective view of the sliding lock; and

Fig. 5 is a diagrammatic view similar to Fig. 1 showing a modified form of the invention.

The numeral 10 designates a railway rail having the usual bottom flange 11 supported on a tie plate 12 resting on a cross-tie 13. The flange 11 is engaged by a rail anchor comprising a yoke 14 having a hook 15 at one end shaped to fit the edge of the flange 11, the hook being continued by a reinforcing rib 16 which extends beneath the body of the yoke 14. The body portion of the yoke 14 comprises a plate which extends beneath the flange 11 and is flared laterally to increase the width thereof at the side of the rail opposite the hook 15. The anchor plate may be provided with a projection 17 which engages the edge of the tie plate 12.

The yoke 14 is provided with a T-head 18 extending along the edge thereof opposite the hook 15. The T-head 18 is inclined slightly relatively to the edge of the rail flange 11 when the clamp is in place with the central plane of the hook normal to the rail, as shown in Fig. 1. The top bead of the T-head may be removed adjacent the point of the projection 17, as shown at 20, to prevent interference between the T-head and the rail flange. A locking member 21 is provided with a recess 22 shaped to fit the

T-head 18 and with a slot 23 for receiving the yoke 14 adjacent the T-head. The locking member is provided with a web or jaw 24 which fits between the lower flange of the T-head 18 and a rib 25 on the lower face of the clamping plate to guide the locking member as it is slid along the T-head 18. The upper jaw 26 of the locking member rests upon the upper face of the rail flange 11. A wedge-shaped tongue 27 extends downwardly from the upper jaw 26 at the outer side of the recess 22 and is interposed between the edge of the rail flange 11 and the T-head 18. The jaw 24 is provided with a shoulder parallel to the inner face of the tongue 27 for engaging the lower flange of the T-head 18.

In applying the anchor to a rail, the hook 15 is placed in engagement with one edge of the rail flange and the point of the projection 17 is placed against the tie plate 12. The sliding lock 21 is then slid over the end of the T-head 18 in the manner indicated in Fig. 3 with the T-head entering the recess 22. The lock is driven toward the tie plate 12 by blows struck on the side of the lock. As the sliding lock moves toward the tie plate the projection 17 will be drawn transversely of the rail by the wedging action of the tongue 27 between the T-head and the edge of the flange 11. This will cause the hook 15 to tightly grip the edge of the flange and lock the anchor firmly on the rail. The fact that the sliding lock is driven along the edge of the anchor plate toward the tie plate insures tight contact of the anchor plate against the tie plate so that when the anchor is gripped to the rail it will be in position to prevent the rail from sliding along the tie in one direction. If it is desired to lock the rail from movement in either direction, anchors will be applied at opposite sides of the tie plate or at opposite sides of alternate tie plates, or at other intervals, as required. It will be seen that the sliding part is located at the side of the rail so that it is not necessary to reach beneath the rail to secure the parts together.

The entire anchor includes but two parts and all that is required to apply the parts is a sledge hammer or other suitable device for driving the sliding lock on the connecting T-head. To remove the anchor it is only necessary to drive the lock backwardly off of the T-head. The sliding lock is preferably provided with reinforcing ribs or flanges

29 at the opposite sides thereof to provide sufficient strength without undue amount of material.

It will be apparent from Fig. 1 of the drawing that when the locking member 21 has been driven past the center line of the hook 15 the tension of the locking member on the head 18 will tend to draw the end of the head 18 adjacent the tie plate 12 away from the rail and impart a rotary movement in a clockwise direction to the entire rail anchor. This will cause the rail anchor to grip the flange in such a manner that pressure between the point 17 and the edge of the tie plate 12 will increase the grip of the anchor on the rail for the reason that the force will tend to rotate the anchor in the same direction as the tension exerted by the wedging member 21. If desired, the parts 20 may be so proportioned that this tendency of the locking member 21 to rotate the rail anchor in a clockwise direction, as viewed in Fig. 1, will take place at a position reached earlier by the locking member in its movement on to the head 18. This may be done by proportioning the parts of the anchor so that the hook 15 will occupy a position further from the plate 12 than that indicated in Fig. 1 of the drawing. If the 30 parts are so proportioned that the edge of the anchor plate farthest from the tie plate 12 is substantially parallel to the edge of the tie plate the rotary movement exerted by the locking member 21 will begin as soon as the locking member is in position on the head 18. This arrangement is illustrated diagrammatically in Fig. 5 of the drawing.

I claim:—

1. Means for holding a rail against longitudinal movement with respect to its tie and tie plate comprising a rail anchor comprising a member extending transversely of a rail and having means at one end thereof for engaging one edge of a rail flange, and a wedging member slidably engaging the opposite end of said transversely extending member for locking said transversely extending member to said rail flange in abutting relation with said tie plate on an adjacent cross tie.

2. Means for holding a rail against longitudinal movement with respect to its tie and tie plate comprising a rail anchor comprising a yoke having a hook at one end thereof for engaging one edge of a rail flange, a guide at the opposite end of said yoke, and a wedging member slidably mounted on said guide for engaging the opposite edge of said rail flange to lock said yoke to said flange in abutting relation with said tie plate on an adjacent cross tie.

3. A rail anchor comprising a yoke extending beneath the lower flange of a rail and having a hook at one end thereof for engaging one edge of said flange, said yoke

having a T-head extending across the opposite end thereof and having an abutment member at one end of said T-head for engaging a tie plate, and a locking member slidably mounted on said T-head and having means thereon for engaging said rail flange to lock said yoke to said rail flange.

4. A rail anchor comprising a yoke for extending beneath the lower flange of a rail and having a hook at one end thereof for engaging one edge of said flange and a T-head at the opposite end thereof, and a locking member slidably mounted on said T-head for locking said yoke to said rail flange, said locking member having upper and lower jaws provided with abutments for engaging the flanges of said T-head and having a wedging member on said upper jaw for engaging the edge of said rail flange.

5. A rail anchor comprising a yoke having a hook at one end thereof, said yoke being tapered with the wider portion at the end opposite said hook, a projection on said yoke at the wider end thereof for engaging a tie plate, a T-head extending along the end of said yoke opposite said hook, said T-head being disposed at an inclination to a line normal to the center line of said yoke, and a U-shaped locking member having a recess for engaging said T-head and having upper and lower jaws provided with shoulders spaced apart to receive the portion of said yoke adjacent said T-head, one of said jaws having a wedge-shaped tongue thereon interposed between said T-head and the edge of a rail flange to which said anchor is attached.

6. A rail anchor comprising a yoke having a hook at one end thereof and a T-head at the opposite end thereof inclined at an angle to a line normal to the center line of said yoke, a rib on the lower face of said yoke parallel with said T-head, and a locking member having a lower jaw interposed between said T-head and rib and having an upper jaw provided with a wedge-shaped tongue interposed between the upper flange of said T-head and the edge of a rail flange to which said anchor is secured.

7. A rail anchor comprising a yoke extending beneath a railway rail and having means for engaging one edge of the lower flange of said rail, said yoke having an abutment member at the opposite end thereof for engaging a tie plate, and means for exerting tension on said yoke at the side adjacent said abutment member on a line extending normal to said rail through the point of connection of said yoke with the edge of said rail away from said tension exerting means.

In testimony whereof I have signed my name to this specification on this 19th day of October, A. D. 1926.

ALPHONSO T. PALMER.
